UNITED STATES PATENT OFFICE.

ROBERT L. PAPPY, OF DAYTONA, FLORIDA, ASSIGNOR TO EAST COAST PRESERVING COMPANY, OF DAYTONA, FLORIDA, A FIRM.

SLICING MACHINE.

1,403,619.

Specification of Letters Patent. Patented Jan. 17, 1922.

Application filed July 16, 1919. Serial No. 311,206.

To all whom it may concern:

Be it known that I, ROBERT L. PAPPY, a citizen of the United States, and a resident of the city of Daytona, in the county of Volusia and State of Florida, have invented 5 certain new and useful Improvements in Slicing Machines, of which the following is a full, clear, and exact description, reference being had to the accompanying drawings, 10 forming part of this specification.

My invention relates to machines for slicing fruits, and particularly the softer fruits, such as oranges and grape fruit.

In the treatment of such soft fruits as 15 oranges, grape fruit, lemons and the like, the great difficulty is to get a clean slicing which is uniform, without mashing up the fruit or crushing it, and the principal object of my machine is to provide an apparatus or 20 machine which will accomplish a proper slicing of such soft round fruits.

In addition to the fundamental object above noted, it is my purpose in this invention to provide a machine which is capable 25 of sufficient speed in operation to be efficient and of considerable safety against injury to the operator.

These objects and other advantages to be noted I accomplish by that certain construction and arrangement of parts to be herein- 30 after more specifically pointed out and claimed.

In the drawings,

Figure 1 is a top plan view of the device. 35 Figure 2 is a end elevation thereof taken from the driving end of the shaft.

Figure 3 is a side elevation of the machine.

Figure 4 is a detail vertical section of the post for detachably retaining the shaft.

40 The machine as shown in the example selected for illustration of the principles of my invention comprises a table 1, which mounts at one end a motor 2, carrying a rapidly revolving knife disk 3. It is this 45 disk which slices the fruit, and the balance of the mechanism deals with the means for mounting the fruit and feeding it against the knife.

The shaft which is fed toward the knife 50 is shown in this embodiment of the machine at 4, and is provided with two journals, one of which is swiveled, and the other of which is provided with a latch for auto-

matically opening and engaging the shaft during the operation of the machine as will 55 be noted.

Describing first the latch device, there is a hollow or grooved post 5, within which is a plunger or latch 6, pressed upwardly by a spring 7. The housing is mounted in the 60 table by means of a suitable fitting 8, and is located toward the end of the machine away from the slicing blade. The upper end of the hollow post is provided with a partial journal member 9 for the shaft 4, and the 65 latch is formed at its upper edge with a journal face 9^a to match the face 9 and practically complete the journal for the shaft. The latch further has a beveled contact surface 10 which, when the shaft is 70 forced against it, will cause a depression of said latch.

In order to provide the largest possible amount of bearing surface for the shaft in the latch member, I provide for an arcuate 75 path for said member to assume during its depression. This path is provided for by means of a pin 11 in the latch and a curved slot 12 in both sides of the post to receive said pin. The latch has an operating finger 80 6^a by which the operator can depress it to release the shaft, and at its lower end the slot 12 is formed large enough at 12^a, so that the pin 11 may be inserted by forcing down the latch beyond the point to which it 85 will be carried after the handle is mounted thereon.

In advance of the latch post for supporting the shaft is the swiveled post 13, which has secured fast or integral with its upper 90 end the sleeve 14. This sleeve is cut away as to its upper half adjacent the middle portion thereof and is provided with a movable member, 16, which is movable to complete the shaft housing of the sleeve. This member is hinged at 15 and is threaded at 15^a, at the portion where it enters the cut-away part of the sleeve. It has also a handle 17.

By raising this member, the shaft 4 is free to slide in the sleeve, but when it is 100 depressed the threads thereon engage the threads 4^a on the shaft, resulting in the shaft being caused to feed forwardly when properly revolved. To withdraw the shaft, or move it either way, for that matter, in the 105 sleeve, all that is necessary is to raise the

threaded member, which will permit the easy sliding of the shaft to whatever position is desired.

While I do not wish to confine my invention to the exact form of thread on the shaft and the threaded member, or "split nut" member, I find it valuable to provide a flat topped thread in order to cut down wear,— thus a $\frac{1}{4}$ U. S. standard thread cut on an 10 $\frac{11}{16}$ inch rod.

For receiving the fruit, the end of the shaft is provided with a dish-shaped plate 18, at the center of which extend a plurality of prongs 19. I prefer three in number. 15 The shaft is further provided with lock nuts 20 for limiting the motion thereof to the right, and the nuts 21 for limiting its motion toward the left, considering the machine placed as shown in the drawings.

20 The end of the shaft away from the slicing knife is equipped with a friction wheel 22, having a handle 23 for manual operation. For mechanical operation, a drum 24 is mounted on the table of the 25 machine in a position to frictionally revolve the wheel 22. This drum may be driven by a shaft 26, that receives its power from a belt 27 and pulley 28 on the motor that drives the knife.

30 As so constructed, the operation of the device is as follows. The operator first releases the latch device so that the pronged end of the shaft can be swung around toward him and away from the knife. He then mounts 35 the fruit on the prongs pushing it home against the dished backing plate. The shaft easily swings on the swiveled post that carries the "split nut" device, and when the fruit is mounted is swung back, thereby 40 automatically tripping the latch and entering the journal in the latch post. Maintaining the split nut or threaded member out of operation, the shaft is thrust forward to a point that will bring the fruit fairly close 45 to the knife. The threaded member is then lowered and held down by the operator and the friction wheel, or manual operation by means of the handle, will feed the fruit slowly forward as controlled by the threads 50 on the shaft.

The knife is set so that it will just clear the prongs, which said prongs should take up but little more space than the core of the fruit. The revolution of the knife and 55 the fruit will then cause a slicing of the fruit in a continuous thin sliver of a depth equal to the threads on the shaft. The dished backing plate for the fruit is quite essential, as it holds the fruit against being 60 forced out of shape, and provides a fairly large bearing surface for the end of the fruit away from the knife.

The nuts are arranged so that the feed is stopped just before the knife would be 65 in a position to strike the dished backing

plate or cup, in which the fruit is seated. As soon as the limit of the feed has been reached, or sooner, if desired, the operator trips the latch journal device to release the shaft so that it can be swung around on 70 the swiveled post for the operator to remove the sliced fruit and replace an unsliced one, operating the split nut device as desired to allow the shaft to remain in the most convenient position for operation, after which 75 the operation is repeated.

The operation of the friction drum is believed to be obvious without full explanation. The reason for the frictional drive is among other things to permit the friction 80 wheel to travel over the drum while it is revolving. It should be clearly understood that either hand or mechanical operation can be used.

The machine can work very rapidly, and 85 does an efficient slicing of soft fruits.

It is not desired that my invention be limited to the precise structure of the latch member, or the threaded member which forces the shaft to travel. Other mechanical devices for accomplishing a like movement could readily be used, my selection for illustration being of parts which are simple of construction and have been proven out as effective in practical work. 95

Having thus described my invention, what I claim as new and desire to secure by Letters Patent, is:

1. In a fruit slicer, the combination with a rotating knife and a rotatable holder for the fruit mounted on shafts parallel to but offset from each other, and means for advancing the holder toward the knife and simultaneously rotating the fruit, said means adapted to rotate the fruit through 100 a complete rotation for each frictional part of an inch of advance, and said rotating knife adapted to cut into the fruit on a line perpendicular to the axis of the fruit. 105

2. In a fruit slicer, the combination with 110 a threaded shaft and a revolving knife, of a swiveled journal for said shaft, having removable threaded means adapted to be brought into engagement with the threads of the shaft for forcing it to advance toward the knife, and an additional journal for the shaft having a releasable element to disengage the shaft. 115

3. In a fruit slicer, the combination with 120 a threaded shaft and a revolving knife, of a swiveled journal for said shaft, having removable threaded means adapted to be brought into engagement with the threads of the shaft for forcing it to advance toward the knife, and an additional journal for the 125 shaft having a releasable element to disengage the shaft, said additional journal comprising a support, a partial journal formed thereon, and a slidale member on the support, having a complementary journal face. 130

4. In a fruit slicer, the combination with a threaded shaft and a revolving knife, of a swiveled journal for said shaft, having removable threaded means adapted to be brought into engagement with the threads of the shaft for forcing it to advance toward the knife, and an additional journal for the shaft having a releasable element to disengage the shaft, said additional journal comprising a support, a partial journal formed thereon, and a slidable member on the support, having a complementary journal face, said slidale member being spring-pressed toward position to complete the journal, and having a beveled face to cause said member to open upon the shaft being forced against it.
5. In a machine of the character described, the combination with swiveled means for journaling a fruit carrying shaft, of a second journal for said shaft comprising a post having a journal formed therein, said journal being in two parts, one of which is slidale on the other, and a curved guide for the sliding connection of said slidale part of the journal, for the purpose described.
6. In a machine of the character described, the combination of a shaft supported thereon, and an operated knife supported thereon comprising a circular disk set off the center of the shaft, means for revolving the shaft, a threaded portion for the shaft, and a releasable means for engaging said threaded portion to bring about an advancement of the shaft.
7. In a machine of the character described, the combination of a shaft supported thereon, and an operated knife supported thereon comprising a circular disk set off the center of the shaft, means for revolving the shaft, a threaded portion for the shaft, and a releasable means for engaging said threaded portion to bring about an advancement of the shaft, said means for revolving the shaft adapted to permit same to travel with the shaft, and comprising a friction wheel on the shaft, and a friction drum driven by the desired source of power.
8. In a machine of the character described, the combination of a shaft supported thereon, and an operated knife supported thereon comprising a circular disk set off the center of the shaft, means for revolving the shaft, a threaded portion for the shaft, and a releasable means for engaging said threaded portion to bring about an advancement of the shaft, said shaft having a fruit support comprising a prong element and a dished backing plate at the base of the prongs.

ROBERT L. PAPPY.
